Primary Examiner — Jennifer Rivard(74) *Attorney, Agent, or Firm* — DLA Piper LLP (US)(57) **CLAIM**

We claim the ornamental design for a razor handle, as shown and described.

DESCRIPTION

FIG. 1 is a front perspective of a razor handle according to an embodiment of our new design;

FIG. 2 is a left elevational view of a razor handle according to an embodiment of our new design;

FIG. 3 is a right elevational view of a razor handle according to an embodiment of our new design;

FIG. 4 is a top plan view of a razor handle according to an embodiment of our new design;

FIG. 5 is a bottom plan view of a razor handle according to an embodiment of our new design;

FIG. 6 is a front elevational view of a razor handle according to an embodiment of our new design; and,

FIG. 7 is a rear elevational view of a razor handle according to an embodiment of our new design.

The broken lines illustrate a button and docketing features and form no part of the claimed design.
